UNITED STATES PATENT OFFICE

HEINRICH SCHRÖDER, OF CASSEL, GERMANY

UMBRELLA

Application filed September 12, 1928, Serial No. 305,438, and in Germany August 16, 1928.

The present invention comprises two characteristic features. The first consists in a case having, besides the usual stiffening ring at that end where the tip of the umbrella stick is received, another rigid ring at the other end where there are the tips of the frame rods when the umbrella is collapsed, and a grip-forming member, may be of an annular shape, from which the rigid ring mentioned, and with it the case, are suspended, there existing, therefore, two grips, viz. the one just mentioned which pertains to the umbrella case, and the grip proper which pertains to the umbrella proper. The first of these grips may be flexible. The other grip or handle which is longitudinally shiftable and can be fixed in its end-positions on the stick of the umbrella. This grip is in one of its end positions when the umbrella is in its position of rest, in a case, and it is in its other end-position when the umbrella is in its position of use, all as fully described hereinafter.

The invention is illustrated diagrammatically and by way of example on the accompanying drawing on which Figure 1 is a side-view of the complete umbrella (umbrella proper and case) in its position of rest, i. e., ready for being suspended from, and carried about by, a hand or the wrist; Figure 2 is a similar view, showing, however, only the umbrella case with its grip, the umbrella proper being removed; Figure 3 is a view of the upper end of the umbrella stick with its shiftable grip, this latter being shown in section, and the figure being drawn to an enlarged scale relatively to Figs. 1 and 2; and Figure 4 shows the same parts of Fig. 3, but the grip having been shifted along upon the stick end and being now in its extended position.

On the drawing, 1 (Fig. 1) denotes the umbrella case, 3 is a rigid stiffening ring at the narrow end of the case, and 5 another, but larger rigid stiffening ring at the other end of the case the ring 3 surrounding the lower stick end 2 of the umbrella, when this latter is in the case, and the ring 5 surrounding the ends or tips 4 of the ribs of the umbrella. 7 denotes an annular grip which is connected to the ring 5 at the points 8 and

9 by means of a few chain-links (or the like). Instead of the rigid annular grip 7 a flexible grip consisting, for instance, also of chain-links or of a cord may be used.

One of the objects of the invention is to give the umbrella as short a length as possible, and for this purpose the length of the stick can be reduced by shifting the stick grip along upon the stick in the direction of the other end of the same. This is done when the umbrella is to be housed in the correspondingly short case 1. In the example shown in the drawing (Figs. 3 and 4) the grip 6 is provided with a longitudinal bore 12, and the stick end 10 with a rubber cap 13, and a cylindrical spring is inserted in the end of the bore. This spring is compressed when the grip is in its retracted position of rest (Fig. 3), and constitutes the means by which the grip is lifted into its extended position, as in Fig. 4.

A lateral pin 14 inserted into the stick end projects into a groove 15 of the grip, whereby this latter is prevented from turning upon the stick end, and a cap nut 19 closes the otherwise open lower end of the grip bore. 16 denotes the usual sleeve which can be shifted along upon the stick and to which the operating and staying rods 17 of the frame are hinged. To the sleeve 16 is attached in the usual manner a flat spring which is imbedded in a longitudinal groove of the stick and is provided with a depressible projection 18, as well as with a pawl 20 located at the free end of said spring within the cap nut 19 (when the grip 6 is in its retracted position, as in Fig. 3). In this position the spring 11 is compressed, but cannot lift the grip into its extended position, because the grip is retained by the pawl 20 by means of the cap nut 19. Only when the member 18 is depressed and thereby the pawl 20 is moved inwardly so as to be withdrawn from the cap nut, the compressed spring can become active and lift the grip 6 into the position shown in Fig. 4, viz. into its position of use.

The strength of the spring is, of course, such that it can support the entire structure of the umbrella, when it is held upwardly in open state. Moving the grip back into its

former position (retracted position) is effected merely by shifting it along the stick until the pawl 20 has re-entered the cap nut 19, as in Fig. 3. The spring 11 has again 5 been compressed during that shifting, and is finally again ready for effecting the operation for which it is intended when the pawl is again released.

When the grip 6 consists of an only moderately rigid material, for instance of celluloid, galalith, or the like, it may be reinforced by a piece of metal tube inserted into the bore 12.

I wish it to be understood that I do not 15 limit myself to all details of the arrangement and combination of parts described and shown. There may be departures in the details without departing from the gist of the invention.

20 I claim:

In combination with an umbrella stick having a longitudinal groove near its holding end; a handle having a longitudinal bore receiving said stick end in it, and having also 25 a longitudinal groove in said bore; a helical compressive spring located in said bore between the end face of the stick and the opposite face of said bore; a pin projecting forth laterally from the stick into said groove in 30 said bore; a cap nut screwed upon the handle end which is located opposite to that enclosing said spring, said nut having a recess at its centre hole; a flat spring located in the longitudinal groove of the stick and being 35 fixed therein; a pawl projecting outwardly from the other end of this spring and being adapted to enter into said cap nut recess when the handle is shifted towards it so as to compress the said helical spring and another projection extending also outwardly from the 40 said flat spring and being adapted to be depressed together with this spring and the pawl by the usual staying rod slide substantially as set forth.

45 In testimony whereof I affix my signature.

HEINRICH SCHRÖDER.
